SPRING MECHANISM FOR AUTOMATICALLY OPERATING SWITCHES

Howard R. Harrison, Upper Darby, Pa., assignor to General Electric Company, a corporation of New York

Application January 10, 1940, Serial No. 313,233

6 Claims. (Cl. 74—97)

My invention relates to a spring mechanism for switches and circuit breakers and more particularly to a spring mechanism for automatically operating switches or circuit breakers by remote control.

Heretofore, it has been the general practice to use a motor or solenoid for directly operating a switch or circuit breaker. Although this method has been satisfactory in some respects, it has the disadvantage that a relatively large amount of current and power is necessary in order to obtain a sufficiently rapid movement of the switch or circuit breaker for opening or closing purposes.

It has also been proposed to store energy in a device over a relatively long period of time either manually or by a low-energy input device and then to use this stored energy to operate the switch or circuit breaker. However, the mechanisms proposed for carrying out this method have been objectionable for several reasons, one being that they occupy considerable space, another being that they are very complicated, and further that they have been relatively inefficient due to the complicated mechanism necessary. Furthermore, many of the prior devices have not been capable of being readily applied to existing nonautomatic switches without any material change in construction and without changing the mode of operation of existing systems.

It is, accordingly, an object of my invention to overcome the disadvantages above noted in connection with the prior art energy-storage devices for automatically operating switches and to provide a more efficient and more positive arrangement for accomplishing the desired result.

It is another object of my invention to provide an improved apparatus for automatically operating a switch, which apparatus occupies a relatively small space as compared to other comparable control apparatus.

Still another object of my invention is to provide an energy-storage device for operating a switch with an improved means for storing energy in said device.

A further object of my invention is to produce an automatic operating mechanism that can be readily applied to existing nonautomatic switches without any material change of construction and without changing the mode of operation of such existing systems.

Further objects and advantages of my invention will become apparent as this description proceeds and the features of novelty which characterize my invention will be pointed out with

particularity in the claims annexed to and forming a part of this specification.

In accordance with the illustrated embodiment of my invention, I provide a mechanism suitable for automatically operating a switch in one direction only, either opening or closing. This mechanism may be charged either by manual means or motor-operated means and comprises two revolving drums surrounded by a large coil spring. Provision is made in the adjacent faces of the drums for latching them together when the coil spring is under tension. By arranging the drums and latching mechanism within the coiled spring a considerable saving in space is accomplished. Should it be desired to operate the switch by remote control, a solenoid arrangement is provided which trips the latching means, thereby allowing the energy stored in the spring to operate the switch. The switch may be operated either to the closed or the open position by means of the mechanism.

For a better understanding of my invention, reference may be had to the accompanying drawings in which Fig. 1 is a cross-sectional view of the automatic operating mechanism of my invention; Fig. 2 is a side view partly in section of Fig. 1; Fig. 3 is a partial sectional view of a portion of the apparatus illustrated in Figs. 1 and 2 to show the tripped or unlatched position of the mechanism, while Fig. 4 is a view similar to Fig. 3 showing the latched positions of the drums; Fig. 5 is a sectional view taken on line 5—5 of Fig. 2, while Fig. 6 is a sectional view taken on line 6—6 of Fig. 2; and Fig. 7 is an exploded view showing the rotating drums of the automatic operating mechanism while Fig. 8 illustrates the operation of the apparatus of my invention.

Referring now to the drawings, I have illustrated my invention as comprising an automatic operating mechanism including a casing or housing 10. This housing is fixedly mounted to some support by suitable bolts, not shown, which may pass through openings 11 provided in extension 12 integrally attached to casing 10. The casing 10 or housing 10 entirely surrounds the internal parts of the automatic operating mechanism except on one side and bottom. The one side of the housing 10 is provided with a cover 13 which includes a bearing 14, while the bottom of the housing is enclosed by the cover 15. Housing 10 is also provided with a bearing 16 within which is rotatably mounted a shaft 17 which has a reduced diameter portion 17' at the end thereof remote from bearing 16. Keyed to the enlarged end of shaft 17 is a lever 18 which is connected through

member 18' (Fig. 8) either to the operating mechanism handle near the ground level, not shown, or suitable motor operating means, also not shown. Also keyed to shaft 17 is a latch drum 19 which can operate only in conjunction with lever 18 since both are keyed to the main shaft 17. Rotatably mounted on shaft 17 is a second drum 20 having a hub extension 21 rotatably mounted within the bearing 14 of end cover 13. A lever 22 is keyed at 23 to the hub extension 21 of drum 20. Lever 22 is connected by suitable means 22' (Fig. 8) to the operating crank of a switch, not shown, which may be either of the tilting or rotating type.

In order to provide an energy-storage means for my automatic operating mechanism which takes up the minimum amount of space, I include a coiled spring 24 which surrounds both drums 19 and 20. One end 25 of spring 24 is arranged to be inserted in one of a plurality of openings 26 arranged in a flanged extension 27 of drum 19. The plurality of openings 26 are provided in order that the initial tension of the spring may be adjusted. A suitable pin 28 is inserted in opening 29 located in the end 25 of spring 24 in order to hold the end 25 of this spring in a particular opening 26 in flange 27 of drum 19. The other end 30 of spring 24 is held in a slotted opening 31 in drum 20 (Figs. 1 and 7). Lever 22 will, of course, rotate in unison with drum 20 since both are keyed together at 23.

Spring 24 must be maintained under torsion so as to operate a suitable switch at the desired time and, to accomplish this purpose, I provide a plurality of latches 32 and 33 mounted in the face of latch drum 19 adjacent drum 20. Latch 32, best shown in Fig. 5, is a trip latch pivotally mounted on an axis 34 which is located on the face of drum 19 adjacent to drum 20 on the left side of the center line of the main shaft 17 (Figs. 2, 3, and 7). Trip latch 32 has a projection 35 which is adapted to be projected out of the plane of the face of drum 19 adjacent drum 20 to abut against stop 36 mounted on drum 20. A spring means 37 tends to rotate trip latch 32 so that projection 35 abuts against stop 36, thereby restricting the travel of trip latch 32 in that direction. Below stop 36 in the face of drum 20 adjacent drum 19 is mounted a latch roller 38 suitably mounted for rotation upon shaft 39 which is supported in bearings 40 projecting from the face of drum 19 (Fig. 7). The lower surface 41 of projection 35 of trip latch 32 is adapted to engage roller 38 as shown in Fig. 5 and, when thus engaged, projection 35 and roller 38 form a latch which prevents rotation of drum 20 and lever 22 in a clockwise direction relative to drum 19 and lever 18, looking from the left end of drum 19 in Fig. 5. Latch 33, pivotally mounted on shaft 42, is located in latch drum 19 on the opposite side of shaft 17 as is trip latch 32 (Fig. 6) and prevents rotation of the drums relative to one another in the opposite direction from the direction of rotation prevented by trip latch 32. Latch 33, however, does not engage a roller as does trip latch 32 but instead slips into a recess 43 provided in the face of drum 20 adjacent drum 19 (Figs. 6 and 7). A spring member 44 tends to bias latch 33 so as to cause it to project into recess 43, whereby the surface 45 at the projecting end thereof engages a corresponding surface 46 provided in recess 43.

Cam members 47 and 47' projecting from the inner face of drum 20 adjacent latch drum 19 tend to hold latch 33 and trip latch 32, respectively, in their unlatched positions during relative ro-

tation of drums 19 and 20 so as not to interfere with the tripping and charging operations of spring 24.

When remote-controlled operation of the switch to which my invention has been applied is desired, a solenoid 48 is energized through suitable means. This solenoid 48 is mounted on an inside face of housing 10 through suitable supporting structure 49 and, when energized, causes the plunger 50 thereof to engage against the extension 51 of trip latch 32. This forces projection 35 of trip latch 32 away from stop 36 against the force of spring 37 and causes the edge 41 to slip off roller 39, thereby allowing drum 20 to rotate in a clockwise direction with respect to the drum 19 and causing the switch, not shown, to be operated through lever 22. Latch 33 slides along the surface of cam 47 and does not interfere with the relative rotation of drums 19 and 20. Similarly, trip latch 32 has the projection 35 thereof sliding along cam member 47' so as not to interfere with the rotation of drums 19 and 20.

In order to cut off the current supplied to the coil of solenoid 48 after operation of the tripping mechanism has occurred, I provide an auxiliary switch 52 suitably mounted within casing 10. This switch is actuated by link members 53 and 54 attached to drum 20 at 55.

When the energy stored in spring 24 is released, it is desired that all the motion caused thereby be transmitted to the switch-operating lever 22. Accordingly, a stop 56 is provided on the exterior of casing 10 to engage with a projection 57 on lever 18, thereby holding lever 18 and latch drum 19 stationary during the release of the energy stored in spring 24.

The operation of the automatic operating mechanism of my invention will be described in connection with an opening operation of a switch although it will be understood by those skilled in the art that this mechanism could equally well be used to automatically close a switch in response to remote control. Figs. 2 and 8 illustrate the arrangement of the mechanism when a switch, not shown, is in the closed position with lever 22 being in the position A₁ and lever 18 being in the position B₁ as shown in Fig. 8. Lever 18 is prevented from being rotated in a clockwise direction by being connected through 18' to the operating mechanism below, which is locked over center in the closed or upper position. Stop 56 and projection 57 prevent rotation in the other direction. Levers 18 and 22 have a definite angular relation to each other in this closed position, which is maintained in one direction by trip latch 32 being held in engagement with roller 38 by the pressure of small spring 37 and in the opposite direction by latch 33 held in engagement with surface 46 of recess 43 by small spring 44.

When solenoid 48 is energized, it causes plunger 50 to travel upwardly striking extension 51 of trip latch 32, thereby causing trip latch 32 to rotate about axis 34 and also causing roller 38 to rotate on axis 39 due to the friction at the point of contact 41. The rotation of latch 32 causes it to slip off roller 38 and permits drum 20 and lever 22 to rotate clockwise looking from the direction of drum 19. This rotation is caused by virtue of the stored energy in spring 24. As the drum 20 rotates the projection 35 of trip latch 32 is held open by rubbing against cam face 47' projecting from the surface of drum 20 adjacent drum 19. Similarly, latch 33 rides along the surface of cam 47, thereby allowing free rotation of drum 20 relative to drum 19. Drum 19 and lever 18 do not ro-

tate when the switch, not shown, is opened by virtue of the energy stored in spring 24 because they are held in position by the operating mechanism, either manual or otherwise, associated with lever 18 and member 18' and also by stop 56 and projection 57. When the spring energy is released, lever 22 assumes the position A₂ shown dotted in Fig. 8.

In order to reset the spring 24, the operating handle 18' associated with lever 18 is brought down to the open position, which causes lever 18 and drum 19 to rotate clockwise, referring to Fig. 8. This brings trip latch 32 to the position so that the projection 35 is forced into engagement with roller 38 and latch 33 is forced into recess 43 by means of springs 37 and 44, respectively. While drum 19 is being rotated by lever 18, the spring is wound up, causing it to be charged when latches 32 and 33 drop into their respective positions. During this part of the operation, the switch, not shown, remains in the open position with the lever 22 in the position A₂ in Fig. 8. By charging the spring, lever 18 is moved from the position B₁ to the position B₂. By this arrangement, the effort required to charge the spring is independent of and, consequently, not added to the force necessary to close the switch. Fig. 3 discloses the tripped or unlatched position of the drums when drum 19 is still in the position illustrated in Figs. 1 and 2 but lever 22 has been rotated to the position A₂ by virtue of the energy stored in the spring. Fig. 4 discloses the drums when the levers 22 and 18 are in the positions A₂ and B₂, respectively, of Fig. 8, that is, when the spring has been charged but the switch, not shown, is still in the open position.

When the two drums 19 and 20 are in their latched position thereby maintaining the spring 24 in the charged condition, levers 18 and 22 are locked together so that the switch, not shown, may be closed by moving lever 18. It will be understood, of course, that the switch may be either opened or closed by movement of lever 18 when the drums 19 and 20 are latched together.

While I have shown and described a particular embodiment of my invention for automatically operating a switch or circuit breaker, I do not desire my invention to be limited to the construction shown and described for it will, of course, be obvious to those skilled in the art that changes and modifications may be made without departing from my invention and I, therefore, aim in the appended claims to cover all such changes and modifications as fall within the true spirit and scope of my invention.

What I claim as new and desire to secure by Letters Patent of the United States, is:

1. In a control apparatus for a switch, the combination of a plurality of drums coaxially mounted for relative rotation with respect to one another, energy-storage means surrounding said drums, latching means mounted in the face of one of said drums adjacent the other drum for holding said drums in fixed relationship to each other, and means for tripping said latching means so that energy-storing means causes rotation of one drum relative to the other.

2. In a spring-operated mechanism for controlling a switch, the combination of a pair of lever arms, a pair of drums, one each of which is fixedly attached to one of said lever arms, said drums being coaxially mounted and relatively rotatable with respect to each other, a spring surrounding said drums and having the ends thereof attached to one each of said drums, a plurality of latches mounted in the face of one of said drums, a plurality of members mounted on the face of the other drum for cooperating with said latching means to hold said drums in fixed relationship with one another when energy is stored in said spring, and tripping means for releasing one of said latches from said members whereby rotation of one of said lever arms and drum relative to the other lever arm and drum is caused by the stored energy in said spring.

3. In a control apparatus for a switch, a switch-operating member, a coiled power spring for supplying the energy for operating the switch, means including a drum and latching means mounted within said coiled spring for releasably holding said spring in wound position, and means for releasing said holding means.

4. In a control apparatus for a switch, a switch-operating member, an energy-storage device comprising a coiled spring, means for releasably holding the energy stored in said spring comprising a plurality of drums and latching means mounted within the confines of the said coiled spring, means for connecting said energy-storage device with a switch so as to transmit the energy stored in said device when released to operate said switch, means for releasing said energy stored in said spring, and means for charging said spring independently of the operation of said switch.

5. In a spring-operated mechanism for operating a switch, the combination of a plurality of drums coaxially mounted for relative rotation with respect to one another, energy storage means surrounding said drums, latching means mounted in the face of one of said drums adjacent the other drum, stop means mounted in the face of said other drum cooperating with said latching means for holding said drums in fixed relationship with respect to one another, means for tripping said latching means so that said energy storage means causes rotation of one of said drums relative to the other, and means for holding said latching means inoperative during said relative rotation.

6. In a spring-operated mechanism for controlling a switch, a switch operating member, an energy storage device comprising a coiled spring, means for releasably holding the energy stored in said spring comprising at least one drum and latching means mounted within the confines of said coiled spring, means for connecting said energy storage device with said switch-operating member so as to transmit the energy stored in said device when released to operate said switch, means for charging said spring independently of the operation of said switch, and means for manually operating said switch without affecting said energy storage device.

HOWARD R. HARRISON.
